UNITED STATES PATENT OFFICE

ROY A. NELSON, OF CHICAGO, ILLINOIS, ASSIGNOR TO CHICAGO RAILWAY EQUIPMENT COMPANY, OF CHICAGO, ILLINOIS, A CORPORATION OF ILLINOIS

STEEL DOOR CONSTRUCTION

Application filed August 19, 1927. Serial No. 214,000.

This invention relates to metal door constructions.

Metal doors particularly car doors are subject to extremely rough usage and in order that they may be conveniently handled cannot be too heavy. It is very difficult to obtain a metal door which is sufficiently strong to withstand all the stresses to which it is likely to be subjected and at the same time have the door of the requisite lightness.

It is the primary object of this invention to provide a metal door which is of the requisite lightness and at the same time of adequate structural strength.

It is further an object of this invention to provide a metal door having the aforementioned characteristics which is simple of construction and may be economically manufactured.

It is also an object of this invention to provide an efficient metal door which is so constructed that it will not collect water in any of its joints and thereby avoids the formation of rust.

Other and further objects of this invention will be apparent as the same becomes better understood from an examination of the specification and claims in connection with the accompanying drawings, wherein:

Fig. 1 represents a front elevational view of a metal car door embodying this invention.

Fig. 2 is an enlarged fragmentary sectional view taken at the line 2-2 of Fig. 1,

Fig. 3 is an enlarged fragmentary sectional view taken at the line 3-3 of Fig. 1,

Fig. 4 is a fragmentary vertical top section showing a modified form of the door where-
in the door is hung from a track,

Fig. 5 is a fragmentary vertical bottom section showing a modified form of bottom for the door,

Fig. 6 is a similar section showing another modified form of bottom for the door where-

in the door is mounted on a track at the bottom of the door, and

Fig. 7 is a similar section of a similar modification.

Referring to the drawings more particularly, reference character 8 represents generally a car door including in this instance three vertically arranged panels 9, 11 and 12. Panels 9 and 11 having adjacent overlapping edges and panels 11 and 12 having adjacent overlapping edges, said edges extending horizontally between the vertical edges of the door.

A Z-bar 13 is riveted by a series of rivets along one of its flanges to the upper edge of the panel 9 for stiffening the upper edge of the door. A pair of vertical Z-bars 14 and 15, respectively, one for each of the vertical edges of the door are provided for stiffening said edges and are similarly riveted thereto.

The Z-bars 13, 14 and 15 are each disposed on the outside of the door with their respective inner flanges riveted thereto and their outer flanges extending inwardly toward the central portion of the door. The opposite ends of the outer flange of the Z-bar 13 are provided with angular plates 16 and 17, respectively, which are riveted to said ends and the corresponding upper ends of the Z-bars 14 and 15.

The lower edge of the panel 12 may be stiffened by any suitable stiffener for example, the T-bar 18.

Pressed steel bars 19 and 21 in the form of channel plates with flanges are provided for reinforcing the door. One of these bars is provided for each pair of overlapping edges of the panels, the bar 19 having its upper flange disposed between the overlapping edges of the panels 9 and 11. The lower marginal edge 20 of the panel 9 is struck outwardly somewhat in order that it may project over the upwardly disposed flange of the bar 19, the remainder of said panel remaining flush with the adjacent panel. The upper

marginal edge 11^a of the panel 11 extends beneath the upwardly disposed flange of the bar 19 and said flange is riveted between the overlapping edges of the two panels by a series of rivets 22. The lower flange of the bar 19 is riveted to the panel 11 by another series of rivets 23. The upwardly disposed flange of the bar 19 being beneath the edge 20 instead of on top of the same will be shed by said edge and caused to flow downwardly over said bar without any possibility of it collecting and causing rust to form between said bar and the surface of the door.

The box-like structure of the bar 19 and the panel beneath provides exceptional strength and further rigidity is provided by riveting the outer portion of the web of bar 19 at its ends to the outer flanges of the respective Z-bars 14 and 15.

The reinforcing bar 21 is similar in all respects to the bar 19 and is disposed between the overlapping edges of the panels 11 and 12 in the same manner as said bar 19 is disposed between the overlapping edges of the panels 9 and 11. Likewise the bar 21 is riveted to the panels 11 and 12 and the Z-bars 14 and 15 in a manner corresponding to the bar 19.

The Z-bar 13 at the top edge of the door may be substituted for by different forms of bars, for example, a bar 22a such as shown in Fig. 4 and having a cross section similar to that of the Z-bar but being provided with an upper horizontal flange 23a whereby the door may be carried on rollers 24 supported on a track 25.

The lower edge of the door may in place of the T-bar 18 be provided with a Z-bar 26 or other form of stiffener. As shown in Figs. 6 and 7 a pair of bars may be provided at the bottom of the door for cooperating with a bottom track or anti-friction carriage thereon.

It will be apparent that the aforescribed door is of exceptional strength without the use of an excessive amount of metal.

It will also be apparent that the door is of simple construction and may be economically manufactured.

I am aware that many details may be varied throughout a wide range without departing from the principles of this invention and I therefore do not wish to be limited to the details shown or described.

I claim:

1. A railway car metal door comprising a plurality of panels one below the other with their edges overlapped, each of said panels consisting of a sheet substantially flat throughout its area, side framing members formed separately from said sheets and applied to the front and rear edges of the door and extending outwardly from the plane of said sheets, a reinforcing element formed separately from said sheets and members and extending between said framing members

with its inner portion secured to at least one of said sheets and with the ends of its outer portion secured directly to the outer portions of said side framing members to form with the adjacent sheet a girder across said door with its chords tied to inner and outer portions respectively of said framing members.

2. A railway car metal door comprising an inside flat body consisting of a series of panels arranged one below the other from top to bottom of the door with each upper panel overlapping the one below it and each of said panels consisting of a sheet extending throughout the width of the door and being substantially flat between its edges, separately formed upright framing members secured to the side edges of said sheets and comprising commercially rolled Z-bars, each having one flange applied to said sheets and having the other flange spaced from said sheets, the latter mentioned flanges on said members projecting towards each other, and a separately formed reinforcing element of U-cross section with flanges on its legs, said elements extending across said sheets with its flanges secured thereto substantially throughout their length and with its web spaced outwardly from the face of said body and secured to the latter mentioned flanges of said Z-bars, said element and the adjacent part of said sheets forming a closed box-like girder across the door.

3. In a railway car metal door, a flat sheet extending from side to side of the door and forming a body panel, a separately formed U-like reinforcing element with flanged legs extending across said sheet with the edge of the flange of one of its legs aligned with the upper edge of said sheet, a second flat sheet forming a body panel and positioned above said first mentioned sheet with its lower portion overlying said flange, securing elements through the upper portion of said lower sheet, said flange, and the lower portion of said upper sheet, and a line of securing elements through the lower flange of said element and said lower sheet whereby said flat sheet and said element form a closed box-like girder across said door.

4. A railway car metal door as described in claim 3 which also includes upright framing members at the sides of said door including webs extending outwardly from the plane of said door and spaced slightly from the ends of said reinforcing element, each web having a flange spaced from the body panel and overlying and directly secured to the web of said reinforcing element, there being a space between the end of said reinforcing element and said framing web to provide for drainage from the interior of the box-like girder.

5. A railway car door as specified in claim 1 which also includes a transverse stiffener member extending across the bottom of the lowermost of said panel sheets and between

said side framing members and having elements spaced transversely of the plane of the door for mounting door supporting structure.

6. A railway car door as specified in claim 2 which also includes a transverse stiffener member extending across the bottom of the lowermost of said panel sheets and between said side framing members and comprising a downwardly facing channel structure for receiving a door supporting anti-friction device.

In witness of the foregoing I affix my signature.

ROY A. NELSON.
